UNITED STATES PATENT OFFICE.

GEORGE W. WATTS, OF BROOKLYN, NEW YORK.

FIRE-ESCAPE.

SPECIFICATION forming part of Letters Patent No. 291,441, dated January 1, 1884.

Application filed February 10, 1883. (No model.)

To all whom it may concern:

Be it known that I, GEORGE W. WATTS, of Brooklyn, in the county of Kings and State of New York, have invented a new and Improved Fire-Escape, of which the following is a full, clear, and exact description.

This invention consists of the combination and arrangement of parts, substantially as hereinafter fully set forth and claimed, where-
10 by the force of gunpowder or similar explosive may be brought into use for elevating ladders from the ground or pavement to the roof or windows of buildings in case of fire, whereby the inmates of the building may es-
15 cape and the firemen ascend and descend.

Reference is to be had to the accompanying drawings, forming part of this specification, in which similar letters of reference indicate cor-
20 responding parts in all the figures.
Figure 1 is a broken side elevation of a fire-
man's hose-truck illustrating my invention as applied thereto. Fig. 2 is a front elevation of the cross-piece of the truck on which the
25 mortar is swiveled, the cross-piece being pro-
vided with the holders in which the ladders
are placed for firing, and with an ammunition-
box. Fig. 3 is a detailed view of the chain
ladder; and Fig. 4 is a detailed view of the
30 projectile, connecting-chain, and grapnel or
anchor.

The hose-truck A is of ordinary construc-
tion, except that it is provided with the up-
right side pieces, B B, which support the ends
of the cross-piece C.

Upon the cross-piece C is swiveled the mor-
tar D, and at the sides of the mortar are placed
and held in the cross-piece the ladder-holders
E E, in which the chain ladders F are placed
35 at the time of firing, and from which they are
elevated by the ascent of the projectile.

G G are the projectiles or balls that are
adapted to be fired from the mortar D. These
are attached to the chain ladders F by the
short chains f, which have the swivels a formed

in them so that any revolution of the projectile 45
in its flight will not be communicated to the
ladder, and attached to the connecting-chains
f, near the balls, are the grapnels or anchors
H, that will catch upon the roof or window-
casing and hold the ladder in case the ball or 50
projectile should fail to do so.

Under the cross-piece C, in the center, is
placed the box J, in which the powder for
charging the mortar is carried.

With this device a ladder may be elevated 55
to the roofs of high buildings or to any story
thereof in a very expeditious and practical
manner, so that in case of fire the inmates may
be rescued, and so that the firemen may quickly
ascend for effective work toward extinguish- 60
ing the fire and saving lives and property.

The chain ladder F is by preference formed
with the chain cross-pieces or steps g, and with
the plain iron bars g', at intervals, which serve
to hold the main side chains of the ladder apart, 65
and also as steps in the ladder; but I do not
confine myself to this form of ladder, as any
form of flexible ladder may be used.

Having thus fully described my invention, I
claim as new and desire to secure by Letters 70
Patent—

1. The chain ladder F, having the projectile
G attached to it by the swiveled chain f, in
combination with the grapnel or anchor H,
substantially as and for the purposes set forth. 75

2. The combination, with the projectile G,
of the ladder F and swiveled chain f, connect-
ing the ladder and projectile together, whereby
any revolution that the projectile may have
will not be communicated to the ladder, sub- 80
stantially as and for the purpose set forth.

3. The cross-piece C, provided with the hold-
ers E and box J, in combination with the mor-
tar D, chain ladder F, and projectile G, sub-
stantially as and for the purposes set forth.

Witnesses: GEORGE W. WATTS.
